Primary Examiner — Kelley Donnelly(74) *Attorney, Agent, or Firm* — Daniel Boudwin; Global Intellectual Property Agency LLC(57) **CLAIM**

The ornamental design for a view of the slotted and double sided article support, as shown and described.

DESCRIPTION

FIG. 1 is a rear perspective view of a slotted and double sided article support of the present invention;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.
